The ornamental design for a water closet, as shown and described.

DESCRIPTION

In a preferred embodiment, the nature of this product is as a plumbing fixture primarily useful for receiving solid and liquid waste from humans.

FIG. 1 is a left, top, front perspective view of a water closet embodying my new design;

FIG. 2 is a top plan view thereof;

FIG. 3 is a left side elevational view thereof, the right side elevational view being a mirror image of the left side shown; FIG. 4 is a front elevational view thereof;

FIG. 5 is a rear elevational view thereof;

FIG. 6 is a bottom plan view thereof;

FIG. 7 is a left, top, front perspective view of a second embodiment;

FIG. 8 is a top plan view thereof;

FIG. 9 is a left side elevational view thereof, the right side elevational view being a mirror image of the left side shown; FIG. 10 is a front elevational view thereof;

FIG. 11 is a rear elevational view thereof; and,

FIG. 12 is a bottom plan view thereof.

The broken line representations of holes in FIGS. 1, 2, 4, 6-8, 10, and 12, of a cap in FIGS. 1, 3, 5, 7, 9, and 11, and of mounting structure in FIGS. 6 and 12, are for the purpose of illustration only, and form no part of the claimed design.
